UNITED STATES PATENT OFFICE.

JOHN H. KERSTING AND VINCENT J. KERSTING, OF NEW YORK, N. Y.

FERRULE.

Application filed February 2, 1922. Serial No. 523,737.

To all whom it may concern:

Be it known that we, JOHN H. KERSTING and VINCENT J. KERSTING, citizens of the United States, residing at New York, in the 5 county of New York, State of New York, have invented a new and useful Ferrule, of which the following is a specification.

This invention aims to provide novel means whereby the ends of a tubular metallic member may be held together so securely that they cannot be separated by any force short of one which would work a destruction of the member.

The device is of general application, but 15 is adapted to be used as part of a paint brush, and when so used, will present a smooth surface which will not interfere with the introduction of the handle or the bristles.

20 It is within the province of the disclosure to improve generally and to enhance the utility of devices of that type to which the invention appertains.

With the above and other objects in view, 25 which will appear as the description proceeds, the invention resides in the combination and arrangement of parts and in the details of construction hereinafter described and claimed, it being understood that, within 30 the scope of what is claimed, changes in the precise embodiment of the invention shown can be made without departing from the spirit of the invention.

In the accompanying drawings:—

35 Figure 1 shows in side elevation, a device constructed in accordance with the invention; Figure 2 is a side elevation wherein the structure is viewed at right angles to the showing of Figure 1; Figure 3 is a section on the line 3—3 of Figure 2; Figure 4 is a section on the line 4—4 of Figure 2; Figure 5 is a section on the line 5—5 of Figure 2.

40 In carrying out the invention, there is provided a tubular metallic member 1, the ends of which are denoted by the numerals 2 and 3. The end 2 has a hook-shaped bead, comprising a body 4 a lip 5 and a bend 6 connecting the lip with the body. The end 50 3 is supplied with a hook-shaped bead, including a body 7 a lip 8 a bend 9 connecting the lip and the body, and an offset shoulder 10 connecting the body 7 with the end 3 of the tubular member.

The hook-shaped beads above described 55 are interengaged as shown in Figures 4 and 5, the shoulder 10 bearing against the bend 7, so that the joint at the point indicated by the numeral 12 is inappreciable. Recalling that Figures 4 and 5 are drawn on a greatly 60 enlarged scale, it will be obvious that when the device is made of metal of the thickness usually employed for paint brush ferrules, stove pipes and the like, the inner surface of the ferrule, at the point 12 will be practically smooth.

The parts 4, 8, 7 and 5 are bent outwardly to form spaced bosses 11, the bosses on the said parts 4, 8, 5 and 7 being interlocked. Owing to the interlocking of the bosses, the 70 ends 2 and 3 of the ferrule will be held tightly together and, when the ferrule is used as a part of a paint brush neither the swelling of the bristles nor the swelling of the handle, due to moisture, will have the 75 slightest effect in bringing about a separation. The spaced bosses 11 may be of any desired form. As shown in the drawings they are of quadrilateral outline, oppositely disposed angles of the bosses being located 80 in a straight line which is parallel to the axis of the tubular member 1—an observation which will be understood readily when Figure 2 of the drawings is examined. Although the specific shape of the bosses above 85 alluded to is not insisted upon, it is useful, in that, when the bosses are constructed and arranged as above set forth, any paint or other liquid on the outside of the tubular member 1, will flow readily, longitudinally 90 thereof, the bosses 11 shedding the paint or other substance, and permitting the same to run longitudinally of the tubular member.

If desired, the tubular member 1 may be circumscribed by the usual ribs 14, common 95 in devices of the kind described, and forming no part of the present invention.

The bosses 11 are struck outwardly and not inwardly. Consequently, the inner surface of the tubular member 1 is not encumbered, but is smooth, it being possible to introduce the handle of a paint brush into the tubular member and with equal facility, to introduce the bristles of the brush thereinto.

Having thus described the invention, what 105 is claimed is:

A device of the class described comprising a tubular member provided at its ends with

oppositely extended interengaged hook-shaped beads, the beads being distorted to form interlocked bosses; the bosses being of quadrilateral outline, oppositely disposed angles of the bosses being located in a straight line which is approximately parallel to the axis of the tubular member.

In testimony that we claim the foregoing

as our own, we have hereto affixed our signatures in the presence of two witnesses.

JOHN H. KERSTING.
VINCENT J. KERSTING.
